CLAIM

The ornamental design for a yacht, as shown and described.

DESCRIPTION

- 1.1 is a top, rear, and left-side perspective view of a yacht showing our new design;
1.2 is a top, front, and left-side perspective view thereof;
1.3 is a rear elevation view thereof;
1.4 is a bottom plan view thereof;
1.5 is a front elevation view thereof;
1.6 is a right-side elevation view thereof;
1.7 is a left-side elevation view thereof; and
1.8 is a top plan view thereof.

The broken lines in the reproductions/drawings illustrate portions of the yacht that form no part of the claimed design.
